JOHN H. CARROLL, OF DE SMET, SOUTH DAKOTA.

COMBINED CAR AND HOSE COUPLING.

SPECIFICATION forming part of Letters Patent No. 478,400, dated July 5, 1892.

Application filed August 24, 1891. Serial No. 403,540. (No model.)

To all whom it may concern:

Be it known that I, JOHN H. CARROLL, of DeSmet, in the county of Kingsbury and State of South Dakota, have invented a new and useful Combined Car-Coupling and Hose-Coupling, of which the following is a full, clear, and exact description.

The object of this invention is to provide an improved car-coupling and combine there-with an improved hose-coupling for an air-brake, so that the coupling together of two cars will simultaneously effect a coupling of hose-sections for air-brakes that are on the car-coupling heads of the connected cars.

15 To this end my invention consists in the construction and combination of parts, as is hereinafter described and claimed.

Reference is to be had to the accompanying drawings, forming a part of this specification, 20 in which similar letters of reference indicate corresponding parts in all the figures.

Figure 1 is an end elevation of a car body and frame with the improvement thereon. Fig. 2 is an enlarged reverse plan view of two 25 car-frames broken away with the improved car and hose coupling, on each car in coupled condition. Fig. 3 is a side view, broken, of two cars and the improved couplings thereon in coupled adjustment. Fig. 4 is a plan view, 30 enlarged, of one car-coupling head and one-half of an air-brake hose-coupling in place thereon. Fig. 5 is a reverse plan view of the parts shown in Fig. 4. Fig. 6 is a side view of the car-coupling head and air-brake coupling-section shown in Fig. 4. Fig. 7 is a transverse 35 section of the car-coupling and air-brake coupling shown in Fig. 2 on the line 7-7 in said figure. Fig. 8 is a transverse section of the parts shown in Fig. 4 on the line 8-8 in 40 said figure, and Fig. 9 is a reduced broken sectional side view of a car-frame and a coupling draw-bar supported thereon having a coupling-head pivoted thereto, shown broken away forwardly.

45 The car-coupling is of a side-swinging latch-hook type, having a coupling-head A, that consists of an elongated metallic block parallel on its top and bottom sides, having its rearward portion a nearly square in cross-section, and transversely slotted from the 50 rear end inwardly in a horizontal plane at its

center of thickness for the reception of the flattened end portion of the draw-bar B, which is pivoted therein so as to form a laterally-flexible joint a' between these parts. The 55 coupling-head A is widened at the front of the portion a, producing a lateral abutment b, and integral with this projection a forwardly and laterally curved extension c, that is widened on the side from which the abutment b projects, so as to form a latching-shoulder d, that hooks slightly rearward, and forwardly of said shoulder is laterally converged to produce an arrow-shaped nose d' on the coupling-head. 60

From the knuckle-joint connection a of the coupling-head A with the draw-bar B the latter is extended a proper length for effective service, preferably in the form of a cylindrical rod that is supported by a bracket-plate 70 C, (shown in Fig. 9 in complete form,) provided with two depending parallel ears e, through which the draw-bar slides, two spiral springs D, pressing against a central pin or flange e', which is affixed to the draw-bar, 75 serving to cushion against percussion and draft strain sustained by the coupling.

The bracket-plate C is secured upon the car-frame by any suitable means centrally between the longitudinally-extending timbers 80 E of the same and at a proper point from their front ends, so that the coupling-head A may rest its rear portion a upon the transverse bar f and slide thereon, said bar being attached by its ends upon the forward ends 85 of the timbers E. The forward side of the abutment-piece b on the coupling-head A is curved inwardly and rearwardly, so as to provide a shoulder b' for the impinge of the nose on a similar coupling-head when a coupling 90 together of two heads is effected, the formation of the part b serving to retain two coupling-heads in interlocked condition until separated by design.

A transverse slot g is formed in the nose c, 95 (see Fig. 6,) thereby producing two parallel jaws forwardly, which are vertically perforated at g' for the reception of an ordinary coupling-pin when the improved coupling is to be attached to an ordinary car-coupling of 100 the link-and-pin type.

It is necessary for the proper operation of

the device that means be provided for the enforced projection of the coupling-head A in front of the draw-bar B, so as to effect a secure latching attachment of its hook-shoulder 5 d upon a similar shoulder on a mating coupling-head, and also to allow both coupling-heads to yield laterally while such a connection is being effected. To this end a straight plate-spring F is provided for each coupling, 10 which is secured firmly by its front end to the coupling-head A near its center line of draft and rearward of the shoulder b', as at i in Fig. 3, the rear end portion of the spring having a sliding engagement with a slotted 15 lug i', which projects upward from the draw-bar B. The spring F by its lateral elasticity allows the coupling-head to swing sufficiently upon the knuckle-joint a' to connect with another like coupling-head, the force of the 20 spring returning the parts to an aligned condition when the latched attachment of two heads has been accomplished.

Upon the lower side of the coupling-head A one-half section of an air-brake hose-coupling is secured. (See Fig. 5.) Said section 25 G consists, essentially, of an elongated cylindrical chamber flattened on one side a sufficient degree to afford a seat whereon a similar coupling-section is designed to impinge 30 and have an air-tight connection therewith.

Each flattened wall of two coupling-sections G, that together form an air-brake hose-coupling, has an aperture m produced in it for the passage of air from one section into 35 the other section when these are detachably connected.

The preferred means for retaining the coupling-section G upon the car-coupling head A, as shown in Figs. 5 and 6, comprises a perforated depending bracket-block n, through 40 which the cylindrical body of the piece G slides, a spring G' cushioning the latter from jar longitudinally.

Upon the forward portion of the coupling-section G there is a pad n' affixed, which is bent to seat upon the lower surface of the car-coupling head A, whereon it is secured to slide endwise by a keeper-bolt n², that loosely engages a slot n³ in the pad and is screwed into 50 the coupling-head.

The means for connecting the air-brake coupling-section G with the car-coupling head A permits the first-named part to slide a limited distance longitudinally, while lateral movement is prevented, and from the 55 relative position assigned to the coupling-section two mating sections will come into contact when two car-coupling heads are latched together.

Upon each section G of the air-brake hose-coupling a clasping-spring o is attached, having its ends curved divergently to facilitate the attachment together of two coupling-sections, these spring-clasps being adapted to 60 engage the opposed sections automatically and hold them closely when two cars having the

improvement are made to approach near enough to automatically couple them together.

Each coupling-section G is attached by an air-brake hose-coupling p upon a section of 70 hose p', (shown broken off in Fig. 3,) which hose in service leads from a source of air-pressure or a vacuum-chamber, depending upon the system employed, and thereby furnishes a continuous conduit from the front to the rear 75 end of a train of cars.

On the end of the car whereon the improvement is placed a bell-crank lever I is pivoted at the junction of its short limb r with the handle-piece from which said limb projects 80 laterally, the terminal end of the latter-named portion of the crank-lever being jointed to the outer end of a link-bar r', which is pivoted at its opposite end to an ear r² on the outer side of the coupling-head A rearward 85 of the curved wall of the abutment-piece b, to which said ear is attached. A sufficient length is provided for the lever I to allow it to be safely manipulated from the side of a car on which the improvement is placed, 90 which lever by its depression will rock the connected coupling-head outwardly and release the engagement of two of the improved car-couplings and that of the air-brake-hose connections also, as before indicated. 95

On the end of the car-body above the lever I one end of a treadle-lever J is pivoted thereto, so as to permit the portion of the treadle that is to be engaged by the operator's foot to project rearward and laterally and locate 100 it behind a guard-rail M, which serves as a protection to a brakeman when he is operating a brake-wheel M', to set the brakes on the car, the treadle-lever and crank-lever I being connected by a rod N, that is pivoted at its 105 ends to these parts, so that a depression of the treadle-lever will rock the bell-crank lever and push the coupling-head A outwardly, and thereby release the parts which have been in connection, as previously explained. 110

Having fully described my invention, I claim as new and desire to secure by Letters Patent—

1. The combination, with a draw-bar adapted to slide longitudinally on a car-frame and a buffer-spring thereon cushioning the draw-bar in two directions of travel, of a side-latching coupling-head pivoted on the front end of the draw-bar and a plate-spring fastened at one end to the coupling-head and loosely connected with the draw-bar, substantially as described. 115

2. The combination, with a support for a draw-bar, adapted to retain it on a car-frame free to slide longitudinally, an elongated cylindrical draw-bar, and a buffer-spring thereon adapted to cushion the bar against draft force or end-thrust, a coupling-head jointed to swing laterally on the draw-bar front end and provided with a lateral latch-hook, and 120 an abutment-shoulder rearward of said latch-hook, of a flat spring held by one end edge- 125

wise on the coupling-head and loosely connected with the draw-bar, substantially as described.

3. The combination, with a bracket-plate 5 on a car-frame, a cylindrical draw-bar held to slide in lugs of the bracket-plate, a buffer-spring thereon, a side-latching coupling-head jointed to swing laterally on the front end of the draw-bar, and a plate-spring affixed by 10 one end on the coupling-head edgewise and loosely connected at the other end upon the draw-bar, of a supporting-plate transversely secured on the car-frame timbers below the coupling-head, a bell-crank lever pivoted on 15 the car-frame in front, a link pivoted to a short limb of the bell-crank lever and by its other end to an ear on the coupling-head, a

treadle above on the car, and a connecting-rod between the treadle-lever and bell-crank lever, substantially as described.

4. The combination, with a car-coupling head pivoted to swing laterally and connect with a mating coupling-head, of a hose-coupling half-section positively held upon the car-coupling head and movable into position to 20 couple in response to a corresponding movement of the car-coupling head and adapted to couple with a mating hose-coupling section when the car-coupling heads are joined, substantially as described.
